UNITED STATES PATENT OFFICE

95,022

DESIGN FOR A COIN SLOT DEVICE

Arvid Dahlstrom and Peter N. Nelson, Chicago,
Ill., assignors to Developments Incorporated,
Chicago, Ill., a corporation of Illinois

Application February 2, 1935, Serial No. 55,216

Term of patent 7 years

To all whom it may concern:

Be it known that we, Arvid Dahlstrom, a subject of the King of Sweden, and Peter N. Nelson, a citizen of the United States, both residing at Chicago, in the county of Cook and State of Illinois, have invented a new, original, and ornamental Design for Coin Slot Device, of which the following is a specification, reference being had to the accompanying drawing, forming a part thereof.

The figure is a perspective view of a coin slot device showing our new design.

We claim:

The ornamental design for a coin slot device, as shown.

ARVID DAHLSTROM.
PETER N. NELSON.
